BOILER

Cornelius M. Kelley, Raleigh, N. C.

Application May 1, 1935, Serial No. 19,274

8 Claims. (Cl. 122—174)

This invention relates to liquid heaters or vaporizers, and more particularly to devices of this character which are designated as vertical boilers, although certain of the novel features of the 5 invention may be applied to boilers or heaters of various other types.

The general object of the invention is to provide a novel and improved heater of this type which is simple in construction, economical in 10 initial cost and subsequent maintenance, and which is very efficient in operation due to its greatly increased steaming rate and enhanced fuel economy.

Boilers and heaters that have heretofore been 15 employed for the same general purposes as those embodying the principles of the present invention, have been of the so-called vertical tubular type, or have been simple tubeless boilers, in which no means for ensuring a proper circulation 20 is provided. The general inefficiency of these prior constructions is also due to the provision of insufficient combustion space and heating surface which causes unnecessary waste of fuel. On 25 account of the insufficient space provided for the complete combustion of the gases there is a rapid accumulation of products of partial combustion upon the heating surfaces which, in most of these cases, are not easily accessible for cleaning. Furthermore, especially in the vertical tubular boilers of this class the efficiency is 30 further reduced by the accumulation of scale on the internal surfaces of the furnace, tubes, and lower tube sheets. The gas travel is comparatively short and the flow is too rapid for effecting the 35 proper combustion and transfer of the maximum quantity of heat to the water.

These boilers have a relatively slow initial 40 steaming rate due to faulty design and this results in a general sluggishness under a fluctuating load.

Then, too, in the type of boiler under discussion, the top head or flue sheet is dry and, being subjected to the direct flames of the furnace, it is often damaged by overheating. This head is also 45 subject to external corrosion by exposure from open chimneys. The tubes are generally only approximately $\frac{1}{16}$ of an inch thick and frequent renewal is necessary due to such corrosion. Another deleterious effect of the lack of rapid initial 50 circulation of the water in these boilers is the creeping of the furnace plate by unequal expansion before the heat can be transferred through the water to the shell plate; this frequently resulting in broken stay-bolts.

55 On the other hand, the present invention elim-

inates the faults found in the common types of construction and provides a compact steam generator which may be used for all heating and power purposes from those requiring the delivery of one horsepower or more and at pressures 5 from one pound up. In its preferred embodiment, the invention contemplates the provision of a combined fire and water tube which may be prefabricated as a single unit for ready installation in a firebox which may also be easily 10 secured within the boiler shell. This combined tube unit is disposed so as to traverse the firebox and connect the opposite sides of the substantially annular water space surrounding the combustion space. The unit is preferably disposed 15 at an angle of approximately 30° with the horizontal. This arrangement causes an extremely rapid initial circulation of the water from the lower end of the water tube to the upper end thereof and thence back through the main portion 20 of the water space. The fire tube portion of the unit is disposed within the water tube and, for the greater part of its length, is concentric therewith, but is provided at its upper end with a substantially right angle bend whereby 25 this end of the fire tube opens through the wall of the water tube into the upper portion of the combustion chamber. The lower end of the fire tube extends through the adjacent annular water space and opens through the outer wall 30 of the boiler into a suitable flue or stack. This arrangement adds further to the efficiency of the boiler by increasing the length of the path of the gases and introducing a down-draft effect, which provides maximum combustion space and gas 35 travel for a given grate area.

The boiler may be of any desired shape, the boiler and firebox heads being preferably made of sheet steel stampings, and the tube unit of seamless steel tubes which may be pre-assembled and 40 welded to the margins of the proper openings of the furnace. The furnace when complete may then be riveted or welded to the boiler shell.

Since there is no dry space exposed to the combustion gases and since the vessel can hold more 45 water than a boiler of the same size in the other types which have been described, there is far less possibility of damage by overheating, there are no obstructions to cause local accumulation of scale, no tube ends to burn, and no exposed heads or 50 tube sheets to deteriorate prematurely by external corrosion. Furthermore, the thickness of the material of the tube unit is such that these parts will have the same normal life as any other portion of the boiler, thereby eliminating many of 55

the common failures and expensive repairs found necessary in the conventional types.

Further objects and features of novelty will be apparent from the following specification when read in connection with the accompanying drawing in which certain embodiments of my invention are illustrated by way of example.

In the drawing:

Figure 1 is a vertical sectional view of a boiler or heater comprising one embodiment of my invention;

Figure 2 is a horizontal sectional view taken on line 2—2 of Figure 1; and

Figure 3 is a horizontal sectional view similar to Figure 2 but illustrating a modified form of boiler.

The novel heater or boiler will be seen to comprise essentially the outer boiler shell designated generally by the numeral 10, and the inner furnace or firebox shell 12. The two shells may be cylindrical, square, rectangular or of any other desired shape, but Figures 1 and 2 of the drawing show the shells to be cylindrical. The boiler shell 10 includes the side walls 14 and the head plate 15 preferably welded thereto, and is provided with suitable hand hole openings 16 having covers 17 secured to the shell by means of suitable bolt and nut connections 18. The shell 10 is also provided with a larger fuel opening 20 which may be provided with any suitable door or closure. An oppositely disposed opening 22 is covered by the lower end of the flue 23 which is preferably formed of a substantially channel-shaped sheet metal member which is provided with flanges 24 suitably secured, as by welding, to the wall 14 of the boiler shell. This construction permits the utilization of any remaining heat units in the combustion gases by providing a close contact between these gases and the wall of the boiler throughout the entire length of the flue or chimney. A clean-out door 25 is provided in the bottom of the flue 23 through which the fire tube is also accessible.

The firebox shell 12 comprises a sheet metal side wall portion 27 which is coaxial with the outer boiler walls 14 and spaced therefrom to provide the substantially annular water space 28. The head 29 of the firebox unit may be welded to the walls 27 and may be provided with a safety plug 30.

The lower margin of the firebox shell 12 is provided with an ogee configuration as at 32 whereby the rim 33 of the shell may be welded to the lower edge 34 of the outer boiler shell, or as clearly shown in Figure 1 of the drawing. At the margins of the fire door opening 20, the inner and outer shells are both curved toward each other and welded at their meeting edges as shown at 35. Any suitable grate construction indicated grammatically at 36 may be disposed in the lower portion of the firebox shell, and suitable ash pit doors may be provided as convenient.

Other conventional openings may be provided in the shells for drawing off the steam or hot water generated in the water space, supplying feed water, or accommodating gauge glasses or other ordinary equipment. The line 38 indicates the mean water level.

One of the most essential features of the present invention is the provision of the combined fire and water tube unit indicated generally by the reference numeral 40. This unit is preferably constructed of seamless steel tubing and the outer wall 42 thereof encloses the water conduit 43. The unit is disposed crosswise of the firebox or

combustion chamber and is inclined with respect to the horizontal, the preferred degree of inclination being approximately 30° with the horizontal plane. A fire tube 45 is disposed within the water tube 42 and for the greater portion 5 of its length is coaxial therewith. The upper end of the fire tube is curved as at 46 and communicates with the combustion space through an opening 47 in the wall 42 of the water tube. The lower end 48 of the fire tube extends beyond the 10 water tube, traversing the annular water space 28 and discharging through the opening 22 in the boiler shell into the flue or stack 23. The upper end of the fire tube is secured within the opening 47 in the water tube by welding as indicated at 49. The lower end is also preferably welded to the margins of the opening 22 as indicated at 50. The entire unit including the water and fire tubes may be prefabricated and installed in the boiler shell as by welding the water 20 tube portion 42 at its ends within the openings 52 and 53 provided in the firebox shell 12.

In this construction, it will be seen that the lower portion of the water tube 42 receives the most direct heat of the furnace and the circulation is initiated at this point, the water passing upwardly through the water space 43 into the annular water space 28 and around the firebox shell 12 from whence the steam or hot water is taken for use, and the return circulation proceeds again through the lower end of the water tube 42. With this arrangement the initial generation of steam is very rapid and the boiler furnace responds perfectly to the requirements of fluctuating loads.

The combustion gases of the furnace envelop the fire tube-water tube unit 40 and then strike the inner surface of the head 29 of the firebox shell 12. From the upper portion of the combustion chamber the gases then enter the curved 40 upper end of the fire tube 45 and proceed downwardly through the fire tube and thence into the flue 23, where they proceed upwardly in close contact with the wall of the boiler shell. It will thus be seen that not only is there provided by 45 the present novel arrangement a more efficient circulation of the water in the heater or boiler, but the utmost extraction of heat units from the combustion gases is obtained, as well as a greater opportunity for more complete combustion of 50 these gases during their passage through the boiler-furnace.

In Figure 3 of the drawing there is illustrated one alternative form of the invention in which both the boiler shell 100 and the furnace shell 112 are square or rectangular in cross section. The shells are spaced from each other so as to provide water legs 128 which are connected by the combination fire tube and water tube unit 140 which is constructed in exactly the same way 60 as the corresponding unit 40 in the embodiment first described, this unit comprising the outer water tube portion 142 and the inner fire tube 145. A fire door is indicated at 120 and a stack 123 provides the same efficient means for heat 65 utilization and the carrying off of the products of combustion as described in the other embodiment. In this form of construction the two shells may be secured in properly spaced relation by means of the stay-bolts 160.

Besides the numerous advantages of the present construction which have already been discussed, it will be noted that it is necessary to provide only one flue opening through the outer boiler shell 10, namely, that designated 22 into 75

which the lower end 48 of the fire tube discharges. It will also be noted that the seamless tubes 42 for the water tube and the curved tube 45 for the fire tube are stock articles and the unit may be fabricated without the use of special tools, dies, or other machinery and that any modern boiler manufacturing plant could complete a boiler-furnace of this character within a very short time without retooling or installing any of the additional machinery which would be required for fabricating odd or complicated sheet metal shapes.

It will be understood that various changes and modifications can be made in the embodiments illustrated and described herein without departing from the scope of the invention as defined by the following claims.

Having thus described the invention, what is claimed as new and desired to be secured by Letters Patent is:

1. In a liquid heater or vaporizer of the class described, in combination, a vertical boiler shell, an inner firebox shell, said shells defining between them a substantially annular water space, a combined water and fire tube structure traversing the firebox and serving to directly connect opposite portions of said annular space and also to directly connect the firebox with the exterior of the first named shell.
2. In a liquid heater or vaporizer of the class described, in combination, a vertical boiler shell, an inner firebox shell, said shells defining between them a substantially annular water space, a single inclined combined water and fire tube structure traversing the firebox and serving to directly connect opposite portions of said annular space and also to directly connect the firebox with a point exteriorly of the first named shell, and a flue into which the fire tube portion of said structure discharges at said point.
3. A liquid heater or vaporizer of the class described comprising, in combination, a boiler shell, a firebox shell within said boiler shell, a straight, continuous, inclined water tube traversing said firebox shell and serving to connect opposite portions of said boiler shell, a fire tube disposed within said water tube and similarly inclined, the upper end of said fire tube opening directly into the combustion space defined by the firebox shell, and the lower end discharging through the wall of the boiler shell into a suitable smoke flue.
4. A liquid heater or vaporizer of the class described comprising, in combination, a boiler shell, a firebox shell within said boiler shell, a straight continuous water tube traversing said firebox shell, a fire tube disposed within said water tube and substantially concentric therewith, one end of said fire tube being curved to open through the wall of said water tube into the combustion space defined by the firebox shell, and the opposite end of said fire tube discharging through the wall of the boiler shell into a suitable smoke flue.

firebox shell, a fire tube disposed within said water tube and similarly inclined, the upper end of said fire tube being curved to open through the wall of said water tube into the combustion space defined by the firebox shell, and the lower end discharging through the wall of the boiler shell into a suitable smoke flue.

5. A liquid heater or vaporizer of the class described comprising, in combination, a boiler shell, a firebox shell within said boiler shell, said shells 10 being substantially rectangular in cross section and defining between them a peripheral water space, a single inclined water tube traversing said firebox shell, a fire tube disposed within said water tube and similarly inclined, the upper end 15 of said fire tube being curved to open through the wall of said water tube into the combustion space defined by the firebox shell, and the lower end discharging through the wall of the boiler shell into a suitable smoke flue.

6. As an article of manufacture, a unitary firebox structure which comprises a substantially cylindrical shell and a combined fire and water tube unit traversing said shell, said unit comprising a straight outer water tube and an inner 25 substantially concentric fire tube of smaller diameter than said water tube, the water tube opening through the opposite walls of said shell and said fire tube being curved adjacent one of its ends and opening at said end through the wall of 30 said outer water tube.

7. As an article of manufacture, a combined fire and water tube unit adapted to constitute a replaceable prefabricated element in the construction and repair of liquid heaters or vaporizers 35 of the class described, comprising a straight outer water tube and an inner substantially concentric fire tube of smaller diameter than said water tube, one end of said fire tube terminating short of said water tube, being curved, and opening 40 through the wall of said outer water tube, the opposite end of said fire tube projecting beyond the corresponding end of the outer water tube.

8. A liquid heater or vaporizer of the class described comprising, in combination, a boiler shell, 45 a firebox shell within said boiler shell, a straight continuous water tube traversing said firebox shell, a fire tube disposed within said water tube and substantially concentric therewith, one end of said fire tube being curved to open through the 50 wall of said water tube into the combustion space defined by the firebox shell, and the opposite end of said fire tube discharging through the wall of the boiler shell into a suitable smoke flue.

CORNELIUS M. KELLEY. 55
